UNITED STATES PATENT OFFICE.

HENRY S. BOODE, OF ST. LOUIS, MISSOURI, ASSIGNOR TO HANDLAN-BUCK MANUFACTURING COMPANY, OF ST. LOUIS, MISSOURI, A CORPORATION.

LANTERN-FRAME.

No. 911,369.

Specification of Letters Patent.

Patented Feb. 2, 1909.

Application filed July 22, 1908. Serial No. 444,745.

To all whom it may concern:

Be it known that I, HENRY S. BOODE, a citizen of the United States of America, residing at the city of St. Louis, in the State of Missouri, have invented certain new and useful Improvements in Lantern - Frames, of which the following is a full, clear, and exact description, reference being had to the accompanying drawings, forming part of this specification.

My invention relates to the frames of hand lanterns of the kind commonly used in railway service and it has for its object the production of a frame of this description that is simple and efficient in nature and one in which the parts may be readily assembled without the employment of skilled labor.

Figure I is an elevation of my lantern frame with the font receiving hoop partly broken out to afford a view of the hoop. Fig. II is a cross section taken on line II—II, Fig. I. Fig. III is a perspective view of a fragment of the font receiving hoop and one of the vertical guard members illustrating the manner of securing the guard members to the hoop.

In the accompanying drawings: 1 designates the font receiving hoop of my lantern frame which is provided at intervals with vertical slots 2, see Fig. II.

3 are the vertical guard members of the frame having upper and lower portions that are united by guard rings 6 which are preferably threaded through said guard members. The guard members are distanced at their upper ends by an interior separating and resistance ring 7.

At the junction of the upper and lower portions of the vertical guard members 3 are

inwardly extending arms 4 which pass 40 through the vertical slots in the font receiving hoop. These arms are split longitudinally to provide spurs or tongues 5 that are spread laterally in opposite directions at the interior of the font receiving hoop after 45 they have been passed through the hoop and in order that said spurs or tongues will lie flatly against the interior surface of the hoop, as seen in the drawings, to hold the vertical guard members of the lantern frame, securely 50 to the hoop without the employment of any other agency, such as solder, keys or the like applied to the arms of the guard members after they have been seated in the hoop.

I claim:—

1. In a lantern frame, a font receiving hoop provided with slots, a plurality of vertical guard members having split arms extending through the slots in said hoop so as to provide superposed tongues on each guard member extending laterally within and lying against the inner wall of said hoop, and means whereby said guard members are connected to each other, substantially as set forth. 55
2. In a lantern frame, a font receiving hoop provided with slots, a plurality of vertical guard members having split arms extending through the slots in said hoop so as to provide superposed tongues on each guard member extending laterally within and lying against the inner wall of said hoop, and guard rings connecting said guard members, substantially as set forth. 60

HENRY S. BOODE.

In the presence of—
H. G. COOK,
BLANCHE HOGAN.
